ANTIAIRCRAFT PROJECTILE

William E. Smith, Goodland, Kans.

Application February 8, 1941, Serial No. 378,040

2 Claims. (Cl. 102—89)

This invention relates to the class of projectiles and pertains particularly to improvements in projectiles designed for use in anti-aircraft ordnance.

The primary object of the present invention is to provide an improved anti-aircraft shell or projectile, which is so designed that it will cover a relatively wide area when fired and, therefore, will be more effective in bringing down aircraft than would ordinary projectiles which require a direct hit for effectiveness.

Another object of the invention is to provide an anti-aircraft shell and projectile in which the projectile is made up of a number of units which scatter or spread out when fired into the air, and thus cover a larger territory than would be covered by a single projectile such as at present used with a consequent greater effectiveness than the single projectile.

Still another object of the invention is to provide an anti-aircraft shell and projectile in which a novel means is employed for housing the projectile in the shell so that the elements of the projectile will be maintained in a predetermined relation until the projectile actually leaves the barrel of the gun and will then be released to be scattered over a wide range.

The invention will be best understood from a consideration of the following detailed description taken in connection with the accompanying drawings, it being understood, however, that the invention is not to be considered as limited by the specific illustration or description but that such illustration and description constitutes a preferred embodiment of the invention.

In the drawings:

Fig. 1 is a view in longitudinal section of a form of shell and projectile constructed in accordance with the present invention.

Fig. 2 is a sectional view on the line 2—2 of Fig. 1.

Fig. 3 is a view of the major part of the projectile removed from the encasing or restraining housing.

Fig. 4 is a view in longitudinal section of the encasing housing for parts of the projectile.

Fig. 5 is a longitudinal sectional view showing a modified form of shell and projectile.

Fig. 6 is a section on the line 6—6 of Fig. 5.

Fig. 7 is a view in longitudinal section of still another form of the invention.

Fig. 8 is a view in longitudinal section of a further modification.

Fig. 9 is a sectional view on the line 9—9 of Fig. 8.

Referring now more particularly to the drawings, reference will first be made to the form of the invention shown in Figs. 1 to 4, and in these figures the shell or cartridge casing for the projectile is indicated generally by the numeral 1. This casing is formed with a relatively long forward end portion 2 within which the missile is housed.

In accordance with the present invention, the missile consists of a plurality of elements which are discharged from the shell into the air and which spread out after leaving the gun barrel to cover a relatively large area, and such missile as shown in Fig. 1, comprises the forward and rear bodies 3 and 4 and intermediate bodies in the form of chains 5 and 6. To each end of each of the chains 6 is attached a metal ball 6'. Numerous loose shot or balls 7 are enclosed in the shell between the inner and outer bodies 3 and 4, as shown. The bodies 3 and 4 are coupled together by the chain 5, the chain being secured to these bodies at its ends by means of the bolts 8 and 9, or in any other suitable manner, while the ball carrying chains 6, here shown as being two in number, although there may be any desired number thereof, are loose between the bodies 3 and 4, and are arranged to extend longitudinally of the connecting chain 5, as shown.

30 The outer body is provided with a surrounding shoulder 10 and the diameter of this shoulder is substantially equal to the interior diameter of the forward end portion 2 of the shell in which it snugly fits and after it is placed in position therein, the end edge of the portion 2 of this shell is turned or crimped in as indicated at 11, over the shoulder 10 to maintain the body in place.

35 The inner body 4 fits snugly in the portion 2 of the shell and functions as a wad against which the explosive force of the powder charge 12 is applied to force the missile forwardly through the gun barrel.

The outer surface of the inner member 4 is flat and there is interposed between this flat 40 surface and the flat inner surface of the outer member 3, the longitudinally split spacer sleeve 13, which is divided into the two portions 14. The overall diameter of this spacer sleeve is approximately the same as the interior diameter of the reduced portion 2 of the shell, so that it lies snugly within the shell and forms a housing between the inner and outer portions 3 and 4 of the missile for the various chains and the loose shot.

45 It will be readily apparent that when the shell

is fired, the missile will move through the gun barrel in the form of a long projectile and when it leaves the gun barrel, the portions 14 of the split spacer cylinder will fall apart so that the various missiles which make up the complete projectile will be allowed to scatter and, therefore, the airplane or other object fired at will be more likely to be struck by the scattered missiles than would be the case if the projectile consisted of a single body.

In the form of the invention shown in Fig. 5, the shell is indicated at 15 and, like the shell 1, it has the elongated forward end portion 16 corresponding to the portion 2, but this portion 15 is of less length than the portion 2 of the shell shown in Fig. 1. In this construction there is provided an auxiliary shell 17 of cylindrical form, but which is longitudinally divided and is open at its two ends. This auxiliary shell has an overall diameter substantially the same as the interior diameter of the portion 16 into which it extends at one end and in which it is firmly held or secured. Within this auxiliary shell is a longitudinally split spacer cylinder 19 of the same form as the cylinder 13. Within the divided cylinder 19 is a central chain 20 and loose side chains 20', all of which extend longitudinally of the cylinder, the center chain 20 being connected at its ends with the inner and outer members 22 and 23, respectively, which are the same construction as the members 3 and 4. The chains 20' have their ends joined to metallic balls 20''. The outer member 22 has the surrounding shoulder 24 engaged by the inturned or crimped edge 25 of the auxiliary shell.

Fig. 7 illustrates another form of the invention wherein the cartridge case or shell is indicated generally by the numeral 26 and is provided with the reduced forward end portion 27 in which is snugly secured an end of the longitudinally divided cylindrical auxiliary shell 28 which is open at its rear end only. The forward end of this shell is rounded to form a semi-spherical nose 29. Within the auxiliary shell is a longitudinally divided cylinder 30 corresponding to the spacer sleeve or cylinder 13, and within this are housed the several chains 31 and the loose shot 32. This divided cylinder 30 is provided for the purpose of preventing jamming of the shot and projectiles in the gun barrel.

At the inner end of the auxiliary shell and the cylinder 30 is a body 33 of lead or other suitable metal which forms the wad in advance of the powder charge in the shell.

Fig. 8 illustrates another form of the invention wherein the casing is indicated by the numeral 34 and the reduced forward end portion is indicated by the numeral 35. In this form the reduced portion of the casing which corresponds with the portion 2 of the structure shown in Fig. 1, is relatively long as shown, and in the

inner end thereof is secured the heavy metal wad 36 which takes the force of the thrust developed by the powder charge which it maintains in position within the casing. The outer end 5 of the reduced portion 35 of the casing is closed by the nose shell 37 which has a short cylindrical portion 38 which fits tightly in the mouth of the shell. This nose 37 maintains in place within the forward end of the shell, the missiles or projectile charge here illustrated as consisting of chains 39 and loose shot 40.

In view of the foregoing, it will be readily apparent that the several projectiles herein described and illustrated provide a novel and efficient means of bringing down airplanes or other types of airship and also provide a more reliable means of destroying such objects than is provided by the single shot type of projectile where extreme accuracy of aim is required in 20 order to make a direct hit.

What is claimed is:

1. A cartridge, comprising a shell casing having an elongated forward end portion, a disk-like body secured within said forward end portion adjacent the inner end thereof and forming a removable wad for maintaining a powder charge in the casing, a disc like body secured within the outer end of the forward end portion and having an encircling shoulder, the edge of 25 said forward end portion being turned over said shoulder to maintain the last body in place, a longitudinally divided cylinder within the forward end portion of the casing between said bodies for maintaining the latter in spaced relation, 30 a plurality of missiles housed within the space between said bodies, said missiles comprising sections of chain, and one of said chain sections forming a coupling means between said bodies and holding said bodies securely in position 35 against the ends of the divided cylinder.

2. A cartridge of the character described, comprising a shell casing having an elongated forward end portion, a disc-like body secured within said forward end portion adjacent the inner 45 end thereof and forming a removable wad for maintaining a powder charge in the casing, a disc-like body secured within the outer end of the forward end portion and having an encircling shoulder, the edge of said forward end portion being turned over said shoulder to maintain the last body in place, a longitudinally divided cylinder within the forward end portion of the casing between said bodies for maintaining the latter in spaced relation, 50 means connected between and joining the bodies together in frictional contact only against the end of the cylinder whereby upon the escape of the cylinder from the shell casing the cylinder will be released to separate into its halves, and a plurality of missiles 55 housed within the space between said bodies.

WILLIAM E. SMITH.
